US00D450805B1

(12) **United States Design Patent** (10) Patent No.: **US D450,805 S**
Lindholm et al. (45) Date of Patent: **** Nov. 20, 2001**

- (54) **CLASSIC STANDARD HANDHELD SHOWER HEAD**
- (75) Inventors: **Jon W. Lindholm**, Chicago; **Antonio J. Belton**, Hazel Crest, both of IL (US)
- (73) Assignee: **Water Pik, Inc.**, Fort Collins, CO (US)
- (**) Term: **14 Years**
- (21) Appl. No.: **29/134,018**
- (22) Filed: **Dec. 12, 2000**
- (51) LOC (7) Cl. **23-01**
- (52) U.S. Cl. **D23/223**
- (58) Field of Search D23/213, 223, D23/226, 229, 230; 239/394, 461, 462

(57) **CLAIM**

The ornamental design for a classic standard handheld shower head, as shown and described.

DESCRIPTION

FIG. 1 is a right-side perspective view of a classic standard handheld shower head showing our new design;

FIG. 2 is a front elevation view thereof;

FIG. 3 is a left side elevation view thereof, of which the right side elevation view is a mirror image;

FIG. 4 is a top plan view thereof;

FIG. 5 is a bottom plan view thereof; and,

FIG. 6 is a rear elevation view thereof.
